D.C. REGULATOR AND CONTROL CIRCUIT
Knud J. Knudsen, Middlebury, Conn., assignor to Lewis
Engineering Company, Naugatuck, Conn., a corpora-
tion of Connecticut

Filed May 1, 1957, Ser. No. 656,422
9 Claims. (Cl. 323—22)

This invention relates to electrical regulators for maintaining voltages constant, and more particularly to low-power D.-C. voltage regulators.

An object of the invention is to provide a novel and improved transistor and crystal diode type D.-C. voltage regulator adaptable for use with normally constant loads, which regulator counteracts, by means of a variable voltage drop, variations in the supply voltage so as to hold the voltage applied to a load within very narrow limits.

Another object of the invention is to provide an improved D.-C. voltage regulator as above set forth, which employs a load-carrying drop resistor of nominal resistance in the circuit providing the counteracting effect on the voltage variations in the supply.

A further object of the invention is to provide a novel and improved D.-C. voltage regulator with load-carrying drop resistor as characterized, wherein the counteraction of the voltage variations follows the effecting of disproportionate variable auxiliary load currents in the said drop resistor.

Yet another object of the invention is to provide an improved D.-C. voltage regulator having a transistor, crystal diode and drop resistor as above outlined, wherein the variable load-current is effected by a variable auxiliary loading imposed by the transistor output circuit, and wherein the transistor input circuit receives signals which are responsive to the variations in the voltage of the supply.

A feature of the invention resides in the provision of an improved, transistor-type D.-C. voltage regulator employing a load-carrying drop resistor, wherein any rise or fall in the supply voltage causes a disproportionate change in a relatively smaller voltage drop across the load-carrying drop resistor, thereby to effect compensation for such change which is either equal or proportional and opposite thereto under all normal operating conditions.

A further object of the invention is to provide an improved pyrometer bridge having novel and effective cold junction control or compensation which is not only very simple but also extremely effective in reducing error caused by the cold junction of the thermocouple.

Another feature of the invention resides in the provision of an improved pyrometer bridge with novel cold junction compensation, wherein inexpensive and readily available metals are used in the legs of the bridge, to effect the compensation.

Still another object of the invention is to provide a pyrometer bridge having novel and improved cold junction compensation utilizing inexpensive and readily available metals to constitute compensating resistors, wherein the correct resistance values may be readily and accurately determined by relatively simple formulae.

Other features and advantages will hereinafter appear.

In the accompanying drawing, the single figure is a schematic circuit diagram of the novel D.-C. voltage regulator and compensated pyrometer bridge, as provided by the invention.

Referring now to the drawing, there is shown within a dotted block outline indicated at 10 a pyrometer bridge representing a substantially constant main load. Supplying such load with current is a primary source of supply (not shown) which may be connected to a trans-

2

former 11 having terminals 12 and 13 connected to a primary coil 14. The transformer 11 has a low-voltage secondary coil 15 provided with a center tap 16 connected to a ground 17. The outside ends of the secondary coil 15 are connected to silicon rectifiers 18 and 19 having a common positive terminal or cathode 20, thereby to effect full-wave rectification of the secondary output at a voltage somewhat less than half that of the secondary coil. To smooth out the ripple in the rectified voltage, a filter capacitor 21 is provided, connected between the positive supply terminal 20 and a ground 22. The above transforming and rectifying means for the voltage supply may also have a resistor 23 connected to the positive terminal 20, to provide for adjustment of the voltage value as required by the bridge load. The voltage between the output terminal wire 24 of the resistor 23 and the ground is thus available for supplying the bridge load referred to and located in the broken outline 10, such voltage being subject to variation because of variations in the voltage applied to the input terminals 12, 13 of the transformer.

In accordance with the present invention I provide a novel and improved D.-C. voltage control or regulator unit having a transistor and a crystal diode, which unit is characterized by the inclusion of a drop resistor and a variable auxiliary loading circuit connected to the fixed main load. The said drop resistor is made to carry load currents changing disproportionately with variations in the supply voltage, whereby its changing, relatively small voltage drop automatically compensates for said variations so as to maintain a constant voltage at an output terminal of the resistor, for energization of the bridge circuit. As shown, this load-carrying resistor is indicated at 25 in the figure, and has one terminal connected with the wire 24, and a second or output terminal connected to a wire 26 the voltage of which (with respect to ground) is maintained substantially constant despite fluctuations within a specified range in the voltage applied to the input terminals 12, 13 of the transformer 11. The resistor 25 is also termed a "second drop resistor," in the appended claims.

In attaining such constant voltage at the terminal or wire 26, I pass variable current through the drop resistor 25 by means of auxiliary loading imposed by a transistor 27 having a base 28, collector 29, and emitter 30. The transistor 27 may be advantageously of the type classified as NPN, connected so that its emitter is common to both the output circuit of the transistor and the input circuit thereof. I connect the transistor output circuit so as to effect an auxiliary loading through the drop resistor 25, such loading varying automatically in response to variations in the voltage applied to the transformer terminals 12, 13 by virtue of a signal voltage impressed on the transistor input circuit, which signal voltage changes with the voltage applied to the transformer.

By this invention the transistor 27 and the circuit thereof are arranged in a novel manner, in conjunction with a crystal diode and other drop resistors, to effect such variable auxiliary loading for the purpose specified. Accordingly, as shown, I connect the emitter 30 to a ground 32 by means of a wire 33, and connect the collector 29 to a resistor 34 of relatively high value which is in turn connected to the output wire 26 of the dropping resistor 25 to effect the auxiliary loading through the latter in the said variable manner. The above connections constitute the output or auxiliary loading circuit of the transistor 27. The resistor 34 serves to establish a constant power dissipation on the transistor, effecting operation which is free from creep due to local temperature change of the base 28. The transistor input circuit, hereinafter also

termed the "base-to-emitter input circuit," comprises a resistor 36 connected by a wire 37 to the transistor base 38, and connected to a ground 38 by which it is thereby joined to the emitter 30. The resistor 36 is also herein-after termed a "first drop resistor," in the appended claims.

With this organization the voltage drop across the resistor 36 constitutes the input signal which is applied to the transistor 27. Current is supplied to the drop resistor 36, in accordance with this invention, by the provision of a crystal diode 40 connected between the wires 37 and 24 with its polarity opposing current flow from the wire 24 to the ground 38. Considering that the supply line comprising the resistor 23 and wire 24 is positive and that the grounds are negative, the crystal diode 40 is so connected as to operate under reverse breakdown, by having its positive terminal or cathode connected with the wire 24. The crystal diode 40 thus acts as a reference, in the manner of voltage regulator tubes, and will exhibit a substantially constant breakdown voltage across its terminals.

I have found that with a voltage output of 28 at the wire 20, and using a 500 ohm value for the resistor 36, a fairly constant voltage of 7.4 may be produced across the terminals of the crystal diode 40. In consequence of this, variations in the voltage applied to the transformer input terminals 12, 13 will cause the relatively smaller voltage drop across the resistor 36 to vary disproportionately. I have further found that by making the resistor 34 similar in value to the resistor 36, and by making the series load-carrying resistor 25 so as to have a value of 10 ohms, in conjunction with the constant main load represented by the bridge circuit, it is possible to obtain at the output terminal 26 of the resistor 25 a very constant voltage measured to ground.

This is accomplished as follows: Changes in the supply voltage applied to the terminals 12, 13 of the transformer 11, causing the said disproportionate changes in the relatively smaller voltage drop across the resistor 36, will provide a varying input signal for the transistor 27 which thereby varies the auxiliary load effected by the output circuit thereof which is connected to the drop resistor 25. The said loading is such that a disproportionate current change occurs in the resistor 25 with changes in voltage at the terminals 12, 13, and such current change is so termed because percentagewise it is greater, for voltage increments at the terminals 12, 13, than the percentages represented by the increments.

Expressed in another way, a rise in voltage at the terminals 12, 13 will not only cause an increase in current through and voltage drop across the resistor 25 by virtue of the main bridge load (which is fixed), but there will also be an additional current through and voltage drop across the resistor 25 due to a disproportionate increase in the loading provided by the output circuit of the transistor 27. This latter increase in loading is of such value that it will maintain at the output terminal 26 of the drop resistor 25 a substantially constant voltage with respect to ground. Moreover, this regulating action also occurs where the supply voltage applied to the terminals 12, 13 drops. When a voltage drop occurs, the loading imposed through the resistor 25 by the transistor output circuit decreases disproportionately with the voltage drop, thereby lightening the load applied to the output terminal 26 of the dropping resistor 25, with the result that the voltage of the terminal 26 is still maintained constant.

It will be understood that the voltage of the signal applied to the transistor input circuit comprising the base 28 and emitter 30 is determined by the rectifier output voltage at the wire 20 in conjunction with the values of the dropping resistor 36 and the resistor 23 in series with the rectifier output. Where the voltage of the terminal 20 is in the neighborhood of 28 volts, signal voltage across the resistor 36 will be somewhat less than 20 volts, assuming a voltage drop across the diode 40 of 7.4 and a

voltage drop across the resistor 36 of approximately 0.5 volt.

From the foregoing it is seen that I have provided a novel, extremely simple and effective D.-C. voltage regulator comprising in conjunction with the transistor 27 and crystal diode 40, the dropping resistor 25 carrying the load current, such regulator compensating for changes in the voltage applied to the transformer input terminals 12, 13 in a manner that a constant voltage exists at the output terminal 26 of the resistor 25, with respect to ground. Relatively few components are employed, and such components are characterized by mechanical ruggedness, and great electrical and mechanical reliability. Moreover, the sizes of the components are very small, so that the entire voltage regulator need occupy only an extremely small space.

For the purpose of compensating for variations in the functioning of the transistor 27 and diode 40 due to temperature variations, I provide in the main load circuit a temperature-compensating resistor 42, which advantageously may be formed of nickel having a resistance value of 65 ohms or so, such resistor having one terminal connected with the wire 26 and delivering current at its other terminal or wire 43 to the bridge circuit. I have found that with this circuit it is possible to interchange both the transistor and diode and still retain regulator integrity over a very wide range of operation.

The present improved D.-C. regulator as above set forth is advantageously employed in a pyrometer system 30 for temperature indications and control, and for such use a thermocouple 45 may be provided, being made subject to the temperatures being measured or controlled. The thermocouple 45 is connected with a resistance bridge circuit having novel cold junction compensation as provided by the invention, such circuit being enclosed in the broken outline 10. The bridge circuit shown has supply terminals or wires 46 and 47, the latter being connected to a ground 48. Two legs of the bridge may comprise resistors 49 and 50 having approximately 2,600 ohms and 4,585 ohms respectively, such resistors being connected to the terminal 46. The resistor 50 may be connected to a servo-controlled potentiometer resistance 51 of approximately 16 ohms, over which a sliding contact 52 passes, such contact being driven by a servo motor.

By this invention the two remaining legs of the bridge comprise respectively a resistor 55 of constant temperature coefficient of resistance, and two series-connected resistors 56 and 57. The resistor 55 may be of an alloy known commercially as Constantan, or an alloy known as Karma, whereas the resistors 56 and 57 are respectively nickel and copper. The Constantan resistor 55 may have a resistance value of 3.4282 ohms, the nickel resistor 56 may have a resistance value at 30° C. of 1.1868 ohms, and the copper resistor 57 may have a resistance value at 30° C. of 2.2414 ohms. By this organization of the resistors 55, 56 and 57 comprising the remaining two legs of the bridge, I obtain an effective cold junction compensation by which the error introduced in the indications of temperature, and in the control, is maintained at a very low value throughout a wide range of temperatures, the latter for example being as great as from plus 80° C. to minus 70° C. With such organization a zero error may be had at the said temperature extremes and also at zero degrees C., with an error at points in between of less than 1/4 of a degree C., this being a theoretical value. Between temperatures of minus 55° C. and plus 120° C. a maximum error of 3/4 of a degree C. would be obtained. In actual conditions of production, this error would be increased slightly, and a maximum error of one degree C. throughout the entire range could be expected.

Included in the two second-mentioned legs of the bridge is, of course, a portion of the potentiometer resistance 51, and also portions of a calibration resistor 60 of constant temperature coefficient of resistance. The resistor 60 may for example have a value of 1/2 ohm, and

may constitute the resistance element of a potentiometer having a contact 61 connected to the ground wire 47 of the bridge. As shown, the resistor 60 is connected with the resistors 55 and 57, so as to be included in the bridge legs. Adjustment of the contact 61 of the potentiometer resistor 60 enables the bridge to be adjusted for zero indication on a meter included in series with the thermocouple leads 63 and 64 of the thermocouple 45. I have found that, in conjunction with the above set forth cold-junction compensation, the thermocouple lead 63 may be advantageously formed of an alloy known commercially as Alumel, and the lead 64 formed of a metal alloy known commercially as Chromel. The Alumel lead 63 is connected to a terminal or junction 72 disposed between the resistors 49 and 56 as shown, and the Chromel lead is connected to a cold junction terminal 65 to which there is also connected a copper lead 66, the latter going to a coil 67 of a D.C. instrument movement of the D'Arsonval type. The remaining terminal of the coil 67 is connected by a wire 68 with the potentiometer contact 52.

While the values of the resistors 55 and 56 and 57 have been given to four decimal places, obviously from a practical standpoint it is not necessary to adhere rigorously to the last figures. The resistor values as shown may be obtained by use of the following formulae:

$$\begin{aligned} 2H &= XA/B - (YD/E + Z) \\ 2L &= XC/B - (YF/E + Z) \\ X &= Y + Z \end{aligned}$$

where

H =Differential millivolts between $+80^\circ\text{C}$. and 0°C .
 L =Differential millivolts between -70°C . and 0°C .
 A =Nickel sample resistance at 80°C . in ohms
 B =Nickel sample resistance at 0°C . in ohms
 C =Nickel sample resistance at -70°C . in ohms
 D =Copper sample resistance at 80°C . in ohms
 E =Copper sample resistance at 0°C . in ohms
 F =Copper sample resistance at -70°C . in ohms
 X =Bridge nickel at 0°C . in ohms
 Y =Bridge copper at 0°C . in ohms
 Z =Bridge Constantan at 0°C . in ohms

In finding errors at intermediate points, in the temperature range, the coefficient for the sample nickel is taken as X/B and for the copper Y/E .

From temperature versus resistance measurements, the following values were found for the Constantan, nickel and copper used for the resistors 55, 56, 57 and 60.

$$\begin{aligned} X &= \text{Nickel in ohms}=1.1868 \\ Y &= \text{Copper in ohms}=2.2414 \\ Z &= \text{Constantan in ohms}=3.2562 \end{aligned}$$

It will be understood that the bridge circuit and thermocouple as above set forth function in the following manner: After the bridge first has been properly balanced, the temperature of the thermocouple 45 will be translated into a potential and nulled by an opposite potential existing between the junction 72 of the bridge and the potentiometer contact 52, such nulling bridge potential being obtained by suitable adjustment of the contact 52. Thereupon, the position of the potentiometer contact 52 will be indicative of the temperature to which the thermocouple 45 is subjected. Changes in the thermocouple temperature will result in changes in the potential generated thereby, requiring readjustment of the potentiometer arm 52 to effect a nulling of the thermocouple E.M.F. The new position of the potentiometer arm 52 to effectuate this nulling will thereupon be indicative of the new temperature of the thermocouple 45.

Initial adjustment of the bridge is effected in the following manner: The thermocouple 45 is placed in ice, and the potentiometer 60 adjusted to obtain a zero indication on a meter inserted in the thermocouple leads.

It will be understood that the contact resistance at the potentiometer 60 has insignificant effect on the balance of the resistance bridge circuit. Since such contact resist-

ance is part of a resistance of over 1000 ohms and the currents in the two bridge arm circuits which determine the proper voltage relation between points 72 and 51 remain practically constant for contact resistance variations of approximately plus or minus .1 ohm, the contact resistance of the potentiometer arm 52 controlled by the servo motor has no influence, since no current flows at balance.

For the purpose of adapting the bridge circuit for different diodes and transistors having commercial variations, a rheostat or adjustable resistance 75 may be provided, connected to the bridge input terminal 46 and to the output terminal 43 of the temperature-compensating nickel resistor 42. The rheostat 75 may have a movable contact or slider 76, as indicated, to effect a control of the current flowing through the resistance bridge.

It will be now seen that I have provided, for a pyrometer type of temperature indicator and control, a simplified and effective, novel and improved D.C. voltage regulator and resistance bridge having novel and effective cold-junction compensation, whereby the temperature indications and control are accurate within specified, narrow limits over a wide range of temperatures. The organization as above provided is relatively simple in its construction, requiring but small space and being characterized by stability and reliability both from the mechanical standpoint and the electrical standpoint.

Variations and modifications may be made within the scope of the claims and portions of the improvements may be used without others.

I claim:

1. In a voltage control circuit, a transistor having a base, an emitter and a collector; a first voltage-dropping resistor connected between the base and emitter; a rectifier and two resistors all series-connected in the order named, the rectifier being connected to said base and the end resistor of the series being connected to the collector, said end resistor, collector and emitter comprising an auxiliary load circuit; supply and main load circuit leads connected respectively to the ends of that one of the series-connected resistors which is joined to the rectifier so as to bridge the said resistor, the load circuit lead being more remote from the rectifier than the supply circuit lead by the value of the said bridged resistor; and additional supply and main load circuit leads connected with each other and to the auxiliary load circuit having the said emitter.

2. The invention as defined in claim 1 in which the said dropping resistor and the said end resistor have relatively high values commensurate with each other.

3. The invention as defined in claim 1 in which the rectifier comprises a crystal diode characterized by a substantially constant voltage drop across it when a varying D.C. potential of greater value is applied thereto, having a polarity tending to cause reverse current flow through the diode.

4. In a voltage control circuit, a transistor having a base, an emitter and a collector; a first drop resistor having a pair of terminals, said drop resistor being connected across the base and emitter; a circuit including a diode having terminals and resistor means series-connected to said diode, said circuit being connected across the base and collector with the diode disposed between the said resistor means and base; a supply circuit for applying a D.C. potential to those terminals of the said first drop resistor and diode which are remote from each other, the said resistor means including a second drop resistor connected to said supply circuit; and a loading circuit connected to the emitter and to a point on said second drop resistor removed from the supply circuit connection thereto, said second drop resistor having a value such that changes in the voltage drop across it are substantially equal to changes in the D.C. potential of the supply circuit.

5. The invention as defined in claim 4 in which the said resistor means includes an additional resistor of relatively high value as compared with said second drop re-

sistor, said additional resistor and first drop resistor being of commensurate values.

6. In a D.-C. voltage control, a supply circuit having a series dropping resistor; a load circuit connected to the supply circuit to receive energy therefrom; a variable loading means including a transistor having an output circuit connected across the load circuit to augment the load applied to the supply circuit; and signal circuit means connected across the supply circuit ahead of said dropping resistor, supplying the input circuit of said transistor with a signal potential varying with the potential of said supply circuit whereby a rise of supply potential will impose a disproportionately greater loading on the supply circuit and effect a disproportionately greater drop through the dropping resistor, thereby to maintain the load voltage constant, said signal circuit including a resistor bridging the transistor input, said transistor output circuit including a resistor, both said resistors having relatively high values commensurate with each other and said series dropping resistor having a value constituting a small fraction of the value of said two resistors; and another series dropping resistor connected in the supply circuit ahead of both said first-mentioned dropping resistors and said signal circuit means.

7. The invention as defined in claim 1 in which there is an additional series dropping resistor connected in the supply circuit lead ahead of the one series-connected resistor which is joined to the rectifier.

8. In a voltage control circuit, a transistor having a base, an emitter and a collector; a supply circuit for providing a D.-C. voltage which is susceptible of variation; a voltage drop means connected across said circuit, having series-connected components one of which is connected to one side of the supply circuit and manifests a constant drop with changes in current therethrough and the other of which manifests a changing drop with changes in current therethrough, the emitter and base of said transistor

constituting the input circuit thereof and being connected with said other component to receive an input signal varying with the voltage drop across said other component, said base being also connected with the said one component, the collector and emitter of the transistor constituting the output circuit thereof; a load-carrying resistor connected to the said one side of the supply circuit; means connected with the load-carrying resistor, providing an auxiliary load circuit through the transistor via the said emitter and collector thereof, said auxiliary load circuit being energizable from the supply circuit through said load-carrying resistor, and the input signal to said transistor being independent of the voltage drop through said load-carrying resistor, said load-providing means including a drop resistor in the auxiliary load circuit, connected to the load-carrying resistor and to the said collector whereby changes in the voltage drop across said load-carrying resistor are substantially equal to changes in the D.-C. voltage of the said supply circuit; and a main load circuit having a constant load, connected to the common junction of the said load-carrying and drop resistors and to the said emitter.

9. The invention as defined in claim 8 in which the said other component comprises a high-resistance drop resistor, and in which the drop resistor in the means completing the load circuit comprises a high-resistance resistor, said high-resistance resistors having values commensurate with each other and greatly in excess of the value of the said load-carrying resistor.
